UNITED STATES PATENT OFFICE.

JOSEPH J. HAYES, OF LOUISVILLE, KENTUCKY.

DESIGN FOR A BOTTLE.

SPECIFICATION forming part of Design No. 29,616, dated November 8, 1898.

Application filed October 9, 1896. Serial No. 608,419. Term of patent 14 years.

To all whom it may concern:

Be it known that I, JOSEPH J. HAYES, a citizen of the United States, residing at Louisville, in the county of Jefferson and State of Kentucky, have invented and produced a certain new and original Design for a Bottle; and I do declare the following to be a full, clear, and exact description of the invention, such as will enable others skilled in the art to which it appertains to make and use the same.

The invention relates to a design for a bottle; and it consists of a bottle of the configuration shown in the accompanying drawings, in which—

Figure 1 is a perspective view looking downwardly upon the bottle, and Fig. 2 is a similar view looking upwardly.

The leading features of the design consist in the body 1, having a tapering neck 2, having an annular groove 3, from which projects upwardly a hood 4, that entirely surrounds the bottle-neck at a point above said groove and extends entirely over and closes the mouth of the bottle.

What I claim is—

The design for a bottle as herein shown and described.

In testimony whereof I hereunto affix my signature in presence of two witnesses.

JOSEPH J. HAYES.

Witnesses:

W. M. JENKINS,
JOHN S. NOYES.
